UNITED STATES PATENT OFFICE.

ANTONIO MACALUSO, OF GENEVA, OHIO.

SOLE OR HEEL PLATE.

1,406,401.

Specification of Letters Patent. Patented Feb. 14, 1922.

Application filed July 23, 1919, Serial No. 312,767. Renewed August 15, 1921. Serial No. 492,585.

To all whom it may concern:

Be it known that I, ANTONIO MACALUSO, a citizen of the United States, resident of Geneva, county of Ashtabula, and State of Ohio, have invented new and useful Improvements in Sole or Heel Plates, of which the following is a specification, the principle of the invention being herein explained and the best mode in which I have contemplated applying that principle, so as to distinguish it from other inventions.

My invention relates to sole or heel plates for shoes. The design of the invention is to provide a device of this character which shall serve efficiently to protect the sole or heel but which shall not damage the edges of the sole or heel.

The annexed drawing and the following description set forth in detail certain means embodying my invention, such disclosed means, however, constituting but one of the various forms in which the principle of my invention may be exemplified.

In said annexed drawing:

25 Figure 1 represents an elevation of a shoe whose heel and sole are provided with my improved plates;

Figure 2 represents a bottom plan view of said shoe;

30 Figure 3 represents a bottom plan view of one of the plates;

Figure 4 represents a side elevation of the plate shown in Figure 3;

35 Figure 5 represents a central vertical longitudinal section, taken in the plane V—V, Figure 3; and

Figure 6 represents a rear elevation of the plate shown in Figure 3.

In the annexed drawing, my improved 40 plate is indicated by the ordinal 1, same being attached to the sole 2 and the heel 3 of a shoe 4. The attachment is made by the means of holding prongs 5 and 6. The plate 1 is preferably formed of a hard steel 45 member and has, preferably, an oval peripheral edge portion 7 and a plane edge portion 8. The oval edge portion 7 conforms to the shape of the heel or toe, as plainly shown in Figure 2.

50 Now, the holding prongs are so formed upon the body portion of the plate, relatively to the edge portions 7 and 8, as efficiently to hold the plate in a fixed position and yet not damage the edges of the heel or sole.

55 The holding prongs are three in number, in the form of device shown, and comprise

one prong 5 struck up from the material of the body 1 and projecting from the central portion of said body. It is evident that this prong 5 will be disposed a substantial 60 distance from the edges of the heel or sole. Said prong 5 serves, however, efficiently to hold the edges of the heel or sole.

The prongs 6 are two in number, preferably, and are disposed adjacently the greatest diameter of the oval peripheral edge portion 7, illustrated by the dotted line 7'—7', Figure 3. Said prongs 6 also intersect the plane peripheral edge portion 8 and, preferably, are disposed in planes at right angles 65 to said edge portion 8. Now, the said edge portion 8 is substantially less in length than said diameter 7'—7' of the edge portion 7, as plainly indicated by the dotted line 8'—8', Figure 3. The result is that, in any position of the plate in which the oval edge portion 7 conforms to the shape of the sole or heel, the prongs 6 are disposed a substantial 70 distance from the edges of the heel or sole so as not to damage said edges.

I wish to call particular attention to the fact that the pair of holding prongs 6 and the prong 5 are rectangular in cross-section but that the longer dimension of the rectangle of either of the prongs 6 lies in a vertical 80 plane not parallel with the plane containing the longer dimensions of the rectangular section of the prong 5. Preferably, the vertical planes containing these respective longer dimensions are perpendicular to each other. 85 This relative disposition of the prongs 5 and 6 results in a very secure holding of the prongs in the leather because one or more of the prongs is certain to hold efficiently in the grain of the leather. A set of prongs 90 all of which extend in parallel planes, in so far as the respective dimensions of their cross-sections are concerned, either easily are loosened or entirely pulled out or must be bent in order to make them hold. I am 95 enabled by the construction described to use a set of prongs extending parallel one to another, in so far as the face of the body member 1 is concerned, but which are relatively staggered so that corresponding dimensions of their cross-sections do not lie in parallel vertical planes, so that a very efficient holding is obtained.

I have ascertained that a plate formed with holding prongs, in the manner described and hereinafter claimed and as shown in the accompanying drawing, very 100 105 110

efficiently serves to protect weak spots on any part of the heel or sole, especially the toe of a shoe that has worn down, and at the same time obviates all danger of what has 5 heretofore been a great defect in the service of said plates, viz., the damage occasioned thereby to the edges of the heels and soles.

What I claim is:

- 10 1. A sole or heel plate comprising a body member provided with an oval peripheral edge portion and a plane inner edge portion, said body member being formed with a holding prong projecting from its central body portion, and with a pair of holding prongs intersecting the ends of said plane inner edge portion, said inner edge portion being substantially less in length than the contiguous diameter of said oval peripheral edge portion.
- 15 2. A sole or heel plate comprising a body member formed with a holding prong projecting from its central portion, said mem-

ber being formed with a plane inner peripheral edge portion, and a plurality of holding prongs intersecting said plane inner peripheral edge portion. 25

3. A sole or heel plate comprising a body member formed with an oval outer edge portion and a plane inner edge portion, said member formed with a holding prong projecting from its central portion, and a plurality of holding prongs intersecting the plane inner edge portion and disposed at a right angle to said inner edge portion. 30

4. A sole or heel plate comprising a body member formed with an oval outer edge portion and a plane inner edge portion, said member having a holding prong projecting from its central portion, and a holding prong projecting from each side of said 40 plane inner edge portion at a right angle to the last named edge portion.

Signed by me this 15th day of July, 1919.

ANTONIO MACALUSO.
